PERCIVAL GREEN, OF SAN FRANCISCO, CALIFORNIA, ASSIGNOR TO MARSH-ROSS CORPORATION, OF NEW YORK, N. Y., A CORPORATION OF NEW YORK.

MEAT-BLOCK-SURFACING MACHINE.

1,183,813.

Specification of Letters Patent.

Patented May 16, 1916.

Application filed September 16, 1915. Serial No. 50,932.

To all whom it may concern:

Be it known that I, PERCIVAL GREEN, a citizen of the United States, residing at San Francisco, in the county of San Francisco 5 and State of California, have invented certain new and useful Improvements in Meat-Block-Surfacing Machines, of which the following is a specification.

This invention relates to surfacing machines and, more particularly, to apparatus for cutting the top of a butcher's meat block to a plane surface when the same becomes uneven or rough through use.

The object of the present invention is to 15 provide efficient devices of this character which will be convenient to operate and may be readily applied to or detached from a meat block.

The invention consists in the novel construction, adaptation and combination of devices as will be hereinafter described and claimed.

In the accompanying drawings, Figure 1 is a plan view showing a meat block with 25 my invention applied thereto. Fig. 2 is a side elevation of the same. Fig. 3 is a detail vertical section through 3—3 of Fig. 1, and Fig. 4 is a horizontal sectional view through a cable winding barrel and its spin- 30 dle to illustrate the manner of securing the barrel to the latter and for taking up slack from the cable.

In said drawings, the reference numeral 5 designates a butcher's meat block, the top 35 5¹ of which is to be dressed to a plane surface.

According to my invention I provide a box-like frame 6 which may be constructed of cast iron and is provided upon its front 40 wall 6¹ with a plurality of conical protuberances 7 which serve to penetrate into a side of the block to prevent the frame tilting in a lateral direction when it is firmly clamped against the block. The clamping of said 45 frame to the block is attained by means of a cable 8 which embraces the block by a loop, as indicated in Figs. 1 and 2, and has its ends respectively engaged with and then wound about barrels 9 and 9¹ which are 50 mounted upon upright spindles 10 and 10¹ which are journaled in the frame 6 in proximity to the corners remote from the wall 6¹ which is juxtaposed with the block. These spindles are provided with polygonal

upper ends 10² to enable them to be engaged by a wrench or a handle provided with a suitable socket. Intermediate the lengths of 55 said spindles they are each provided with a hole 10³ (Fig. 4) extending diametrically therethrough and a similarly arranged hole 60 9² is provided in each of the barrels.

When the frame is to be attached to a block it is held against the latter, and the cable looped about the block and the cable ends threaded through the holes of the respective barrels and spindles. The ends are 65 then further drawn by the operator through the said holes until the slack is removed from the cable loop and the frame is thereupon rigidly clamped to block by successively turning the spindles through the medium of the referred to wrench or handle. 70 In such operation it is evident that the cable by passing through the barrels and the spindles, will couple them together and by such 75 coupling means the size of the loop in the cable may be readily varied to accommodate blocks of different diameters and shapes.

11 represent ratchet wheels secured to the spindles and are engaged by pawls 12 which 80 are pivotally connected to said frame to prevent any accidental unwinding of the cable from the barrels. Extending longitudinally through the frame is a screw 13 which engages in a nut 14 (Fig. 3) having a socket 14¹ 85 in its top to serve as a seat for the spherical lower end 15¹ of a cylindrical-post 15. This post extends through an aperture 16 in a nut 16¹ which engages the threads of a screw 17 extending transversely through the 90 frame. Said screws are provided with polygonal ends 13¹ and 17¹ whereby they may be rotated by a wrench and are secured against axial movements by set collars 13² and 17². By suitably regulating the nuts 95 14 and 16 through the instrumentality of the respective screws, the post 15 may be adjusted to be in a vertical position or in a position rectangular to the plane to which it is desired to dress the top of the meat block, 100 even though the frame itself may be considerably tilted from the horizontal. The post 15 serves as a pintle for a substantially horizontal arm comprising two members 18 and 18¹ which are jointed or connected together by a hinge pin 19.

At the free end of the outer arm member 18¹ are provided bearings for an upright

arbor 20 having mounted at its lower end a circular saw 21. Said arbor is driven by an electric motor of ordinary or suitable structure which is inclosed in a casing 22 and actuated by a current through wires 23 from a source of supply. Said wires may advantageously extend through a tubular handle bar 24 secured to the motor casing.

The apparatus is attached to the block 5 by clamping the frame 6 thereto, as before explained. The post is then adjusted into upright position, if required, by manipulating the screws 13 and 17. When thus regulated, the operator completes the electric circuit to rotate the saw which is then controlled by the operator to cause it to traverse the top of the block by swinging the same about the axes of the post 15 and the elbow joint of the arm. The saw is most conveniently movable through the agency of the handle bar 24.

What I claim, is:—

1. A block dressing device of the character described, comprising a frame, means 25 for detachably securing said frame to a block, a post, means provided in said frame for regulating the angular position of said post with respect to the frame, a jointed arm supported by said post, an arbor carried by the outer end of said arm, a saw mounted on said arbor, and a motor for

rotating the saw through the medium of said arbor.

2. In a block dressing machine, the combination with an upright arbor, a saw mounted thereon, means to drive said arbor and the saw, an arm carrying said arbor and the driving means, and a post supporting said arm, of a frame, a step-bearing provided in the frame for the post, a post journal bearing provided in the frame above said step-bearing, means for adjustably moving said journal and step-bearing in rectangular relations to each other, and means to detachably secure said frame to a block which is to be dressed.

3. In apparatus of the class described, the combination with an upright post, a saw, driving means for the saw, and operative connections between said post and the saw to enable the latter to be swung in a horizontal plane, a frame, means provided in said frame for supporting the post in various adjusted positions, and means for clamping said frame to the block to be dressed.

Signed at San Francisco, Calif., this 1st day of September, 1915.

PERCIVAL GREEN.
